TURBINE DISC AND BLADE MOUNTING

Joseph Thompson Purvis, Etobicoke Township, Ontario, and Robert Mitchell Sachs, North York Township, Ontario, Canada, assignors to A. V. Roe Canada, Limited, Peel, Ontario, Canada, a corporation

Application September 17, 1953, Serial No. 380,834

7 Claims. (Cl. 253—77)

This invention relates to the rotors of rotary power conversion machines and particularly to those comprising discs having radially disposed open slits angularly spaced around their rims.

In such machines the high temperature working fluid passing through the blading causes the blades and the rim of the disc upon which the blades are mounted to become very hot, whereas the other portions of the disc are usually cooled by some means to preserve the physical properties of the material and to prevent the conduction of heat to the rotor bearings. The resulting temperature differential between the rim and the other portions of the disc, together with the high centrifugal loading to which the disc is subjected under operating conditions, introduces severe internal stresses and these may cause some yield in the material, which in turn will induce other internal stresses when the rotor is stopped and allowed to cool.

Repeated heating and cooling may cause cracking and it has therefore been the custom to provide ample material to absorb all thermal and centrifugal stresses, with the result that the discs have been unduly heavy and structurally inefficient.

To overcome the aforementioned difficulty, radially disposed open slits have been angularly spaced around the rims of such discs, to permit some degree of circumferential expansion and contraction without subjecting the rims to hoop stresses.

However, since there is usually a considerable pressure gradient in the working fluid across a stage, there is a tendency for the hot working fluid to leak through the slits, thus heating and reducing the strength of the rim and the mounting of the blades therein.

It is customary to mount the blades in the rim of a rotor by the provision of dove-tail or fir-tree roots on the blades, which slide, substantially axially of the rotor, into corresponding slots circumferentially spaced around the periphery of the rotor disc. It is, of course, necessary to provide some means of locking each blade against axial movement to retain it in its slot after it has been inserted. This may be achieved by the provision of some dowel or pin, engaging a recess in the blade root transversely of the direction in which the blade is otherwise free to slide in the slot.

It is an object of this invention to provide dowels or pins peculiarly adapted to lock the blades in a rotor disc of the type having radial slits around the rim to accommodate expansion and contraction thereof, and to arrange the said dowels or pins so that they effectively prevent any leakage of the working fluid through the said slits. Other objects and advantages of the invention will be apparent from the following description of a preferred application thereof.

2

In the accompanying drawings, forming a part of this application and in which each reference character denotes the same part in all the views:

Fig. 1 is a side elevational view of a gas turbine jet engine incorporating the invention, partly cut away to show a portion of the turbine rotor disc and blades,

Fig. 2 is a fragmentary front elevational view of an arrangement of the turbine rotor blades on the rim of the turbine disc according to the invention,

Fig. 3 is an axial section of the turbine disc and a blade on the line 3—3 of Fig. 2,

Fig. 4 is an enlarged perspective view of the sealing pin shown in Fig. 3,

Fig. 5 is an enlarged perspective view of a portion of Fig. 3 showing a manner of securing the pin in position after assembly in the rotor, and

Fig. 6 is a view, similar to that of Fig. 3 showing an alternative application of the invention.

In a gas turbine engine such as that shown in Fig. 20 1 air is drawn into an inlet 19 by an axial flow compressor 11 and discharged at high pressure from the compressor into a combustion system 12. The combustion system comprises a plurality of chambers into which fuel is introduced and burned in the aforesaid compressed air, 25 so that the air is discharged at high velocity and high temperature into the turbine 13. The turbine provides the power to drive the compressor 11, through the shaft 14, the exhaust from the turbine being discharged through the tail cone 15 to provide a propulsive thrust.

30 The turbine 13 comprises a rotor disc 16, carrying on its peripheral rim 17 a plurality of radially disposed blades 18. Means not shown are provided for directing a stream of cooling air upon each side of the rotor disc.

As shown in Figs. 2 and 3 each blade 18 is secured in 35 the rim 17 of the disc 16 by a fir-tree root 19 which engages a corresponding slot 17a disposed in the rim axially with respect to the engine. Although the engagement of the root in the slot obviously prevents any radial movement of the blade, the root is free to slide axially along the slot, its movement in one direction being limited by a tang 20, extending radially from the root and engaging a lateral face 21 of the rim 17.

From the bottom of each slot 17a in the disc a radially 40 and axially disposed open slit 22 extending from face to face of the disc and rim extends for a short distance towards the centre or hub of the disc. It terminates in a cylindrical hole 23 of slightly greater diameter than the circumferential width of the slit, that is, the width of the slit in a circumferential direction of the rotor. The axis 45 of the hole 23 is parallel to the axis of the disc. To avoid undue weakening of the rotor disc the holes are arranged at alternately greater and lesser radial distances from the centre of the rotor as shown in Fig. 2.

50 Each slit 22 intersects longitudinally a cylindrical bore or way 24, which may be of the same diameter as the hole 23, disposed obliquely from the end of hole 23 at the face of disc 16 to a point in the root-engaging surface of the slot in the rim; this point is located to register with a transverse recess 25 in the blade root when the tang 20 is in engagement with the face 21. Each of the obliquely directed bores 24 therefore may be said to be in an axial plane of the engine and to intersect at an acute angle a radial plane through the rotor.

55 The blade is positively located within the slot by a tubular pin 26 formed of a wall of resilient elastic material such as Iconel, curved in cross-section as, for in-

stance, to form a generally cylindrical hollow shell as shown in Fig. 4 and disposed in the bore 24.

A tubular pin 26 preferably has a slot 26a along its full length (see Fig. 4), rendering it more resiliently yieldable across its width or diameter. It has a short transverse slot 27 adjacent one end also. The head portion 26b of the pin 26 between the slot 27 and the end 26c adjacent thereto, is accommodated in the recess 25, and the adjacent end 26c of the pin bears against the side of the recess remote from the tang 20 and holds the tang firmly against the face 21.

The outside diameter of the pin is slightly larger than the diameter of the oblique bore 24, necessitating some radial compression of the pin as it is inserted into the radially inner end thereof. However, as the head portion 26b emerges from the bore into the recess 25 it is progressively relieved of this compression until, when the transverse slot 27 emerges from the bore, the head portion of the pin is free to expand to its natural shape. This expansion effectively prevents the pin from being withdrawn from the bore or from inadvertently falling out. To remove the blade from the disc it is necessary to shear the terminal portion from the pin, by forcibly driving the blade root from the slot. Because the pin is under radial compression in the hole and traverses the entire radial length of the slit 22, it effectively seals the slit against any leakage of working fluid from one side of the disc to the other. On the other hand, since the pin is itself slotted it exerts no material restrain upon any expansion or contraction of the rim 17. Thus it will be understood that the pin serves the dual purpose of providing a positive lock of the blade root in its slot, acting in this respect in conjunction with the tang, and of sealing the slit in the disc against leakage.

In the alternative construction shown in Fig. 6 the turbine rotor comprises two substantially parallel discs 16' and 16'' enclosing between their rims 17' and 17'' an annular groove 17a' of fir-tree form in axial cross-section. In this construction the root 19' of each blade 18' is disposed circumferentially of the rotor and is accommodated in the aforesaid annular groove 17a'. As in the previously described construction a radially and axially disposed open slit 22' is provided extending through both rotor discs substantially on the longitudinal axis of each blade 18', to permit circumferential expansion and contraction of the rims 17' and 17'' of the discs.

Each slit terminates in a cylindrical hole 23' or 23'' as the case may be, of slightly greater diameter than the circumferential width of the slot and disposed with its axis parallel to the axis of the discs, and a cylindrical bore 24' of the same diameter as the hole 23' and lying entirely within disc 16', extends obliquely from one end of the hole 23' to a location, in the space defined by the said annular groove 17a' which is in alignment with a recess 25' in the blade root, when the blade is assembled in the rotor.

The blade is secured radially by virtue of the fir-tree configuration of its root in the annular groove defined by rims 17' and 17'', and circumferentially by a pin 26', similar in every respect to the pin 26 of the previously described construction, which is driven through the obliquely disposed bore 24' into the recess 25'. It will be apparent that this pin 26' also serves to seal the slits 22' and 22'' against any leakage of working fluid from one side to the other of the particular rotor disc in which the pin is fitted, but since it is customary to arrange such discs 16' and 16'' with a space 28 between them, at least one of the discs must carry pins 26' in every slit 22' in order to provide a complete seal across the assembly.

The forms of the invention herein shown and described are to be taken as preferred examples and various changes, within the scope of the subjoined claims, may be made in the shape, size and arrangement of the parts.

What we claim as our invention is:

1. In a rotary power conversion machine, a rotor disc

having a slit extending for the full thickness of the disc inward from its circumference, and having a blade slot in its circumference adjacent the slit, a blade slideable in the blade slot, the slot having an axis along which the blade slides, a locking member disposed in the slit at an angle to the said axis and having one end projecting outward into the blade slot, the said end of the locking members engaging the blade and preventing sliding movement of the blade in the blade slot, and means retaining the blade in the blade slot.

2. In a rotary power conversion machine, a rotor disc having a substantially radially disposed slit extending for the full thickness of the disc inward from its circumference to accommodate circumferential expansion and contraction of the disc in operation and having a blade slot in its circumference adjacent the slit, a blade slideable in the blade slot, the slot having an axis along which the blade slides, a locking member sealingly fitting and closing the slit against the passage of working fluid, the locking member being arranged at an angle to the said axis and having one end projecting outward into the blade slot, the said end of the locking member engaging the blade and providing a stop for the blade to prevent sliding movement of the blade in the blade slot, and means retaining the blade in the blade slot.

3. In a rotary power conversion machine, a rotor disc having a substantially radially disposed open slit extending for the full thickness of the disc inward from its circumference to accommodate circumferential expansion and contraction of the disc in operation and having a blade slot in its circumference adjoining the slit, a blade slideable in the blade slot, the slot having an axis along which the blade slides, a pin of width not less than the circumferential width of the slit extending for the full radial length of the slit, the pin sealingly fitting and closing the slit against the passage of working fluid, the pin being arranged at an angle to the direction of sliding of the blade and having one end projecting outward into the blade slot, the said end of the pin engaging the blade and preventing sliding movement of the blade in the blade slot, and means retaining the blade in the blade slot.

4. In a rotary power conversion machine, a rotor disc having a substantially radially disposed open slit extending for the full thickness of the disc inward from its circumference to accommodate circumferential expansion and contraction of the disc in operation and having a blade slot in its circumference in radial registration with the slit, a blade slideable in the blade slot, the slot having an axis along which the blade slides, a pin of width not less than the circumferential width of the slit extending for the full radial length of the slit, the pin being formed of a wall of resilient material curved in cross-section and resiliently yieldable across its width and sealingly fitting and closing the slit against the passage of working fluid, the pin being arranged at an angle to the said axis one end of the pin projecting outward into the blade slot and engaging the blade to prevent sliding movement of the blade in the blade slot, and means retaining the blade in the blade slot.

5. In a rotary power conversion machine, a rotor disc having a substantially radially disposed open slit having parallel facing walls and extending for the full thickness of the disc inward from its circumference to accommodate circumferential expansion and contraction of the disc in operation, each of the walls of the slit having a groove, the grooves being in opposing registration across the slit so as to provide a bore having a width circumferentially of the disc greater than the corresponding width of the slit, and a blade slot in the circumference of the rotor disc in radial registration with the bore, a blade slideable in the blade slot, the slot having an axis along which the blade slides, a pin in the bore and extending at an angle to the said axis and having one end projecting outward into the blade slot, the said end of the pin engaging the blade and preventing sliding move-

ment of the blade in the blade slot, and means retaining the blade in the blade slot.

6. In a rotary power conversion machine, the combination claimed in claim 5 in which the pin is formed by a wall of resilient material curved in cross-section and normally of outside diameter greater than the diameter of the bore, the wall of the pin having a longitudinal slot for its full length.

7. In a rotary power conversion machine, the combination claimed in claim 6 including means for securing the pin in place that comprise a recess in the blade root for loosely receiving the projecting end of the pin, and a transverse slot in the wall of the pin intersecting the longitudinal slot and freeing a portion of the wall of

the projecting end of the pin for expansion in the recess in the blade root beyond the diameter of the bore.
